Morris Eichenblatt,

By his Attorney

Abraham Engel.

UNITED STATES PATENT OFFICE

MORRIS EICHENBLATT, OF BROOKLYN, NEW YORK

CLIP

Application filed November 9, 1928. Serial No. 318,176.

The present invention relates to clips for use with hair waving tubes or the like, and aims to provide certain improvements in such clips.

In the art of hair waving as now generally practiced, the tresses to be waved, after being moistened with a suitable solution, are wound around a form, inserted into a tube of paper, foil or the like, and the ends of the tube sealed with clips which are retained on the tube until the waving operation is completed. These clips have cooperating interengaging or latching means so that the ends of the tube can be crimped around tresses of various thickness. The application of said clips to the tubes is a simple operation. To remove the clips, however, the operator, usually a woman with tender fingers, encounters great difficulty and frequently suffers pain in releasing the latching engagement of the clips. Various forms of clips have been devised to facilitate the releasing action, but so far as I am aware none of these are entirely free from the objections pointed out.

Accordingly, an object of the present invention is to provide a clip for the purpose specified in which the releasing or unlatching of the clip is greatly facilitated. Another object is to provide a clip which is free from sharp lugs or projections which are troublesome to the tender fingers of the operators. A still further object of the invention is to provide a clip which is simple and sturdy in construction, efficient in use and which can be cheaply manufactured.

The foregoing and other objects of the invention I accomplish by providing a clip, the finger engaging portions of which are free from sharp edges and one wherein the operator in grasping said finger engaging portions, simultaneously engages an element which upon applying but slight pressure thereon releases or unlatches the interengaging parts of the clip. The invention also embodies other features of novelty which will be hereinafter more fully described.

A preferred embodiment of my invention is illustrated in the accompanying drawings, 50 wherein:

Figure 1 is a plan view of the clip embodying my invention in open position with a part broken away.

Fig. 2 is an edge view of the clip shown in Fig. 1 looking downwardly from the top 55 thereof.

Fig. 3 is an edge view of the clip shown in Fig. 1 looking upwardly from the bottom thereof.

Fig. 4 is a plan view of the clip in closed 60 or latching position.

Referring to the drawings, the clip may be said to consist of a pair of members which are pivotally connected at their ends as shown at C. Of these members one consists of a single substantially flat element A and the other consists of two coincident substantially flat elements B and B' disposed in parallel spaced relation to each other and between which the lower end of the element A is receivable in the manner of the blade of a pocket knife. The elements are formed with inner curved edges a, b and b', respectively, the edges a and b and b' being complementally curved to engage around a hair waving 70 tube to crimp or seal the same around a tress of hair. To hold the clip members in tube crimping position they are formed with cooperating interengaging means herein shown as comprising a plurality of semi-circular 75 openings D in the body of element A in proximity to its lower end and a struck-up substantially semi-circular tongue or lip E near the lower end of the element B', said lip extending inwardly into the space between the 80 elements B and B' and being of slightly smaller size than the openings D and adapted to snap therein as the element A is positioned between the elements B and B'.

To move the pivoted members into and out of latching engagement the elements A and B are each provided with an integral projecting arm or part F and G respectively, terminating in enlarged circular ends f and g 95 respectively. Although such enlarged flattened ends may serve as finger engaging elements I prefer to free these finger engaging parts from sharp edges and thereby ease the finger gripping engagement therewith. This 100

I accomplish by mounting upon said enlarged ends *f* and *g* separately formed flattened ball-shaped or substantially ovoid members *H*. These members *H* may conveniently be formed in a known manner from sheet metal by a series of stamping operations and assembled on the projections *F* and *G* by the use of suitable dies.

For facilitating the releasing or unlatching of the elements *A* and *B'* or in other words for disengaging the lip *E* from the recesses *D*, the element *B'* is provided with a projection *J* extending at substantially a right angle to the body of said element, said angled portion extending through an opening *g'* in the projection *G*. The free end *j* of said projection *J* is enlarged, rounded and bent to overlie the projection *G* and terminates in proximity to the finger engaging end *H* on the member *B*. From the construction and arrangement of the finger engaging parts of the elements *B* and *B'* it will be at once apparent that as the fingers of an operator simultaneously engage said enlarged ends and pressure is applied thereto that such pressure will cause the body portions of the members *B* and *B'* to move apart out of their parallel relation and that the movement of *B'* will cause the lip *E* to become disengaged from an opening *D* so that the members of the clip can be readily released from their engaging position. To facilitate the entrance of the element *A* between the elements *B* and *B'*, I prefer to outwardly flare the free ends of said elements *B* and *B'* as shown at *b²* and *b³* respectively.

From the foregoing description it will be apparent that I have provided a latching clip which is simple in construction, easy in operation, one which is free from the means which cause the annoyance and pain to the operator's fingers and one which in view of the foregoing characteristics greatly expedites the use thereof.

While I have shown and described a preferred embodiment of my invention, I do not desire to be limited to the specific construction disclosed, since it will be understood that modifications thereof may be resorted to without departing from the spirit of the invention.

What I claim is:

1. A clip comprising a pair of substantially flat elements pivotally connected together near one end and movable about said pivot in parallel planes, one of said elements having a struck-up lip on one face and the other element having a plurality of recesses in its face which is complementary to that having the struck-up lip, said lip being adapted to engage in one of said recesses to latch the elements together and means movable as a unit with one element of said pair of elements adapted to serve as a point of leverage for

moving said element out of parallel relation to the other element to disengage the lip from a recess.

2. A clip comprising a pair of substantially flat elements pivotally connected together near one end and movable about said pivot in parallel planes, co-engaging means on the complementary faces of said elements in proximity to their other end for latching them together, means for moving said elements into and out of latching engagement comprising an integral projecting part on each of said elements, a third element disposed in coincident relation to one of the pair of elements and having a projecting part in substantially coincident relation to the projecting part of said element, the third element having a slot in its projecting part through which an offset portion on the projecting part of the element coincident with said third element extends, whereby said coincident elements are rendered movable as a unit about the pivot, the projecting parts on the coincidentally disposed elements being capable of limited relative movement in a direction transverse to the planes of the elements and adapted for simultaneous engagement by the fingers of an operator, and when so engaged and pressure is applied thereto, one of the elements will be moved to unlatch the co-engaging means on said elements.

3. A clip comprising a pair of substantially flat elements pivotally connected together near one end and movable about said pivot in parallel planes, co-engaging means on the complementary faces of said elements in proximity to their other end for latching them together, means for moving said elements into and out of latching engagement comprising an integral projecting part on each of said elements, a third element disposed in coincident relation to and movable as a unit with one element of said pair of elements having a projecting part in substantially coincident relation to the projecting part of the element with which it is movable as a unit, said last two named projecting parts being capable of limited relative movement in a direction transverse to the planes of the elements and adapted for simultaneous engagement by the fingers of an operator, and when so engaged and pressure is applied thereto, one of the elements will be moved to unlatch the co-engaging means on said elements.

4. A clip comprising a pair of members pivotally connected together at one end, one of said members consisting of two substantially flat coincident elements in spaced relation and the other member consisting of a single substantially flat element mounted between the other two elements in the manner of the blade of a pocket knife, co-engaging means on a pair of complementary faces of said members for latching them together,

means on said members for moving them into and out of latching engagement, and co-operating means on the two elements of the first member for moving said elements apart to disengage the other member therefrom.

5 In witness whereof, I have hereunto signed my name.

MORRIS EICHENBLATT.
